UNITED STATES PATENT OFFICE.

GEORGE H. DERN, OF SALT LAKE CITY, AND THEODORE P. HOLT, OF PARK CITY, UTAH.

ORE-ROASTER.

1,113,961.

Specification of Letters Patent.

Patented Oct. 20, 1914.

Application filed April 9, 1914. Serial No. 830,669.

To all whom it may concern:

Be it known that we, GEORGE H. DERN and THEODORE P. HOLT, citizens of the United States, residing, respectively, at 5 Salt Lake City, county of Salt Lake, State of Utah, and Park City, county of Summit, State of Utah, have invented certain new and useful Improvements in Ore-Roasters, of which the following is a specification.

10 This invention relates to blast ore roasters.

Our object is the provision of a novel ore roaster adapted for carrying out the roasting process set forth in the application of 15 Neils C. Christensen, Jr., and Theodore P. Holt, filed August 3, 1911, Serial No. 642,088 and that set forth in the patent to Wilhelm Buddeus No. 1,079,897, dated November 25, 1913; and still further, adapted 20 for the performance of a blast roasting process embodying improvements on the roasting process of the said application and patent.

Our invention is adapted for the treatment 25 of any metal bearing ore, particularly those ores which require an oxidizing or chloridizing roast preparatory to the extraction of the valuable metals by any suitable solvent.

30 The invention relates, more particularly to the provision of a novel blast roaster adapted for the treatment of ores which are first finely crushed and moistened and (if not carrying the necessary fuel themselves) 35 are mixed with sufficient fuel to adapt them for roasting by internal combustion of the mass, by forcing a blast of air through the charge and for the treatment of the charge in a novel manner.

40 In the present invention we have provided a blast ore roaster embodying improvements and novel features by which loss by volatilization, which in other types of roasters when used for chloridizing 45 roasting is from ten to fifteen per cent., is practically eliminated; a saving of about seventy-five per cent. of the fuel consumed by other roasters is effected; the cost of installation is greatly minimized; the fumes 50 are concentrated and, when desired, may be easily condensed; the roasted product is free from slime and consequently much easier to leach; and dusting, with its considerable loss, is entirely eliminated.

Our ore roaster is continuous in operation 55 to the extent that the fire is never allowed to go out and the roaster is never completely emptied, although it is charged and discharged intermittently; further, the roasting zone is allowed to travel upward until 60 it reaches the top of the charge, or substantially so, whereupon it is dropped suddenly, after which it can again travel to the top. A desideratum in roasting ore by our process is to obviate the occurrence of portions 65 or sections of the charge which offer less resistance than the remaining portions thereof, because such weak places permit a rush of air through them and thus the ore roasts more rapidly at these points than in 70 other portions of the charge. We have found that a continuous discharge of the roasted ore, as has been previously proposed, has invariably cracked the cake, or caused it to settle away from the walls of 75 the roaster, thereby forming air channels. The present roaster is adapted to cause the charge to drop quickly and freely at desired intervals, and while cracks may occur, they may be sealed up with a layer of fresh ore 80 and cause no difference in roasting.

The present roaster maintains a permanent but shifting roasting zone in the columnar charge of ore and removes the roasted ore from beneath the roasting zone 85 at intervals, fresh unroasted ore being added on top as required.

Our invention consists, first, of an open charge-supporting and air distributing grate, a charge-holding or roasting chamber, and an equalizing air pressure box or chamber, relatively arranged so that the blast from said air box or chamber has free access to the charge being roasted and is subject to air pressure control at will; second, a preferred embodiment of said elements, in which the charge-holding and roasting chamber is uppermost, and the equalizing air pressure box or chamber is arranged therebelow, an open charge-supporting, crushing and blast distributing grate being located between the said chambers, the air pressure box or chamber being normally free from contained roasted ore, or substantially so, but also incidentally 100 serving as a hopper for the temporary holding of such portion of the charge as is intermittently crushed and lowered by the 105

grate, until the discharged roasted ore may be removed; third, a novel open charge-supporting crushing grate having relatively movable sections or parts, which preferably travel in opposite directions, together with operating means therefor, said grate being so constructed and related to the walls of the roasting chamber that it is adapted to crush or scrape off the bottom of the roasted ore cake and discharge the broken and roasted ore through and beneath the grate without disastrous pressure on the walls of the roaster and at the same time, insuring a uniform settlement of the roasting charge; fourth, a roasting chamber whose internal size increases toward its lower part where it approaches the grate, which construction prevents the charge from adhering to the side walls and thus insures an even settling through the ore mass when the grate is operated.

The invention also consists in a particular improved grate for an ore roaster; improved means for supporting the grate; the relationship of the said grate to the walls of the upper charge-holding chamber and the lower equalizing air pressure box; and the provision of controlling means for the roasting chamber, whereby the fumes may be taken off, as desired, to a stack or condenser.

The embodiment of the invention disclosed in the drawings and hereinafter described is, in the broader aspect thereof, capable of modification within the spirit and scope of the invention and, except where limited in the appended claims, is to be deemed as illustrative, rather than restrictive, of the scope of the invention.

In the accompanying drawings: Figure 1 is a vertical section through the center of the roaster on the line 1—1, Fig. 2; Fig. 2, a plan view, the cover being removed; Fig. 3, a detail section on the line 3—3, Fig. 1, and Fig. 4, a cross section on line 4—4, Fig. 1.

The body 1 of the roaster is preferably square or rectangular in cross section, having an air box or chamber 2. The roaster is supported by horizontal members 3 carried by posts 4 resting on a suitable foundation. The upper part of the shell has a suitable refractory lining 5 to conserve the heat and protect the shell 1 from corrosive gases. A removable or hinged cover 6 is provided for the normal closure of the roaster and the admission of the ore. A flue 7 connects the roaster with a smoke-stack or condensing chamber.

The grate is composed of a plurality of relatively reciprocatable sections 8 composed of bars 8^a and transverse grate bars 8^b which are connected to and supported by the bars 8^a and are provided on their upper edges with serrations, teeth, or projections 8^c, Fig.

3. The bars 8^a and 8^b may be connected together in any preferred manner. In each grate section 8, the bars 8^a are parallel to each other and the transverse bars 8^b are parallel.

Referring to Fig. 3, to the bars 8^a, which may be angle-iron, are secured guards 11 extending, in each instance, substantially the width of the given grate section 8. The ends of the guards are downwardly disposed, preferably inclined, as shown in Fig. 1.

Extending crosswise of the roaster are stationary channel irons 10 to which are secured, at intervals of the length thereof, roller supporting blocks 10^a which are of more or less dished configuration on their upper faces and are provided with upwardly extending parts 10^b.

Resting on a plurality of the roller supports 10^a are rollers 9 which are preferably provided with heads on their ends 9^a so that they are retained against displacement from the supports 10^a. The guards 11, of which there are two for each grate section 8, rest upon the two rollers 9 provided for that section. Thus, each section 8 of the grate is mounted independently of all other sections thereof. For convenience, however, the channel beams 10 are employed for supporting all of the roller supports 10^a.

The crushing grate sections 8 may be reciprocated in any preferred manner, but we preferably operate them from the same shaft 14 which is suitably mounted in bearings on the frame 3, by cranks or eccentrics 14^a connected to rods 12 on the grate sections by links 13^a, said rods 12 working through stuffing boxes 13 in the shell 1. Preferably, the links 13^a and their rods are set so that contiguous sections 8 of the grate travel in opposite directions in relation to each other. We do not limit ourselves, however, to this construction and operation of the grate, except where specified in the claims. The advantage gained by this opposite travel of the grate sections is that it distributes the crushing strain transmitted through the ore to the roaster shell, whereas if all of the grate sections traveled as a unit, the opposite sides of the shell would be alternately subjected to relatively great pressure. Also, if all the grate sections traveled as a unit they would have a tendency to carry the entire charge bodily back and forth, thereby forming air channels along the sides of the shell. The shaft 14 may be driven in any suitable manner, as for instance, by gearing 15, 16^a, from a shaft 16 having pulley 16^b.

A pipe for delivering the air blast to air box 2 is shown at 17, the latter having perforations or an elongated slot 17^a on its lower side, the nozzle portion of said pipe

being disposed crosswise of the hopper bottom 2 below the grate. A valve 18 controls the air blast. An air-tight door 20 is provided to permit inspection and removal of the grate sections 8. The pipe 17 need not extend into the box 2.

We consider it advisable to provide a smooth interior for the lining 5 and that it be of somewhat greater internal size toward its lower part where it approaches the grate, in order that an even settlement of the charge will occur. Finely divided ore, properly moistened, cakes together in roasting, and by providing the foregoing features, the ore mass may be lowered without disturbing the roasting ore particles in their relation to each other, whereas if the internal size of the roaster is the same from top to bottom or is smaller at the bottom, the charge is liable to "hang up", by adhering to the sides, thus necessitating hand work in relieving this condition. The open construction of the grates permits scraped or broken off parts of the ore cake to drop freely from them. The ends of the grate are overhung by the lower end 5^a of the lining 5. This prevents the ore from getting between the ends of the grate and the wall 5 and prevents breakage due to the crushing action which would otherwise occur at these points. Furthermore, the open grate construction insures an even distribution of the air blast to the charge. The shield bearings 11 prevent dust and ore from having access to the lower bearing members 10^a and prevent clogging of the rollers 9. At the same time, the spacing apart of the bearing members 10^a, permits the material to drop through without accumulation. The air box 2 provides a free air-distributing chamber from which the air blast has access to all parts of the grate and through the latter to all parts of the charge.

The roast may be started in various ways, but the following has been found in practice to give the best results. The grate sections 8 are first covered with a layer of roasted ore lumps of such size that they will not fall through. Three or four inches of fine ore is then spread over the said roasted ore lumps to insure an even distribution of the air. A layer of small pieces of wood to the depth of two or three inches is then placed on the fine ore. Kerosene may be sprinkled over the wood. Upon igniting the wood, a quick spreading of the flame over the entire surface occurs, the air blast being meanwhile regulated by the valve 18. After the wood is burned to coals the first charge of suitably prepared ore is put on. The fuel in the ore becomes ignited and the mass begins to roast, the roasting zone proceeding upward. The cover 6, which has been thrown back up to this time, is now closed, so that the smoke

and gases pass out through flue 7 to a condensing chamber or to a chimney. At intervals the cover is raised and additional charges of ore are added, until the roaster is filled. The roasting zone meanwhile is ascending and finally approaches the top of the roaster, say, to a point about level with the bottom of the flue 7, whereupon the air blast is shut off by closing the valve 18, and the charge is lowered. Up to the time of lowering the charge, the grate sections 8 are allowed to remain stationary, but when the charge is to be lowered, power is applied to reciprocate the grate sections 8. The teeth, projections, or serrations 8^c scratch or scrape and crush or cut off the bottom of the roasted cake and the broken off portions of roasted ore fall through the open crushing grate sections 8 into the hopper 2.

The mounting of the grate sections on the rollers, reduces friction and the grate sections require but little power for their reciprocation, as they roll easily on the rollers 9. When desired, a gate 19 in the bottom of the hopper 2 is opened to discharge the roasted ore into a bin, car, or onto a conveyor or into a launder, as desired.

The charge having been lowered, as described, to the desired distance, and the ore let out of the hopper 2, the gate 19 is closed, the power cut off so that the grate sections will remain stationary, and a fresh charge of ore is delivered into the roaster. The cover 6 is then closed and the valve 18 opened, and the roasting operation is resumed until the roasting zone, by its ascension, finally reaches the desired point where it is advisable to again drop the charge.

In our roaster, the heated air and gases travel in an opposite direction to the ore and it will be seen, therefore, that the roaster applies the principle of "counter currents" to the process of blast roasting in a most economical manner. It also secures an intimate contact between the active gases of the roast and the mineral particles of the ore so as to produce the desired reaction with a minimum of reagents. In the old types of roasting furnaces, the loss of valuable metals by volatilization and dusting often exceeds ten per cent. of the total value of the ore. We have demonstrated on a commercial scale that there is practically no loss of valuable metals when roasted in our roaster and that the gases are entirely free from dust, comparatively cool, and concentrated, and can easily be condensed for leaching purposes; further, that the roasted ore is practically free from slime and is brought to a pervious character which is an ideal condition for subsequent leaching. Many ores are of such a slimy character that solutions will not percolate through them. Our roaster changes their texture so that

they can be leached, which is cheaper than agitation and filtration. We can condense the acid and chlorin from the gas coming from our roaster and utilize them in leaching solutions.

Where the situation demands that a chloridizing roast be prepared, additional reagents, such as salt, pyrite, etc., are added to the mixture before it is charged into the roaster.

In our roaster we provide means for carrying out the Christensen and Holt and Buddeus roasting processes but, in addition, we carry out a new or improved roasting process by new means. The charge is supported by the grate in our invention, free from contact with any previously roasted ore below the grate. The grate is not embedded in ore above and below it as in the Christensen and Holt and Buddeus processes. The provision of the air or wind box 2 which is never filled with ore, causes the blast to be equalized and also to be distributed to all parts of the grate, the latter being constantly subject to the blast, under whatever control of the latter may be exercised by valve 18. The box 2 also acts as a roasted ore collector but its latter function does not interfere with its service as an air or wind box and, in carrying out the process of roasting, we, therefore, not only progress the roasting zone upwardly, as in the Christensen and Holt and Buddeus processes, but, also, support the column of roasting ore while allowing the roasted and scraped off ore to freely drop or fall away from the grate and at the same time have a self-equalizing source of air blast.

Having thus described our invention, what we claim as new and desire to secure by Letters Patent, is:

1. In an ore roaster adapted for roasting a single columnar charge by internal combustion thereof, a charge-holding chamber, a crushing grate consisting solely of independent oppositely movable sections each of open form arranged and adapted for directly supporting the single columnar charge in said chamber and for crushing or disintegrating the ore when said sections are moved, to discharge the disintegrated ore through said grate, means for operating said sections in opposite directions to each other, a combined collecting and air pressure chamber located below said grate and means for introducing a blast of air into said last-named chamber and upwardly through said grate into a charge supported thereon for the purpose of roasting the charge solely by internal combustion thereof.

2. In an ore roaster adapted for roasting a single columnar charge by internal combustion thereof, a charge-holding roasting chamber, a crushing grate consisting solely

of independent oppositely movable sections 65 each of open form arranged and adapted for directly supporting the single columnar charge in said chamber and for crushing or disintegrating the ore when said sections are moved, to discharge the disintegrated ore through said grate, means 70 for operating said sections in opposite directions to each other, said roasting chamber having walls which overhang the ends of the sections of the grate, whereby 75 access of ore between the ends of the grate sections and the walls of the roasting chamber is prevented, a combined collecting and air pressure chamber located below the grate and means for introducing a blast of air 80 into said last named chamber and upwardly through the grate into a charge of ore supported thereon for the purpose of roasting the charge solely by internal combustion thereof.

3. In an ore roaster adapted for roasting a single columnar charge by internal combustion thereof, an upper roasting chamber for holding said charge, an air distributing crushing grate composed of independent, 90 movable crushing parts or sections collectively arranged and adapted for directly supporting a single columnar charge in said chamber, and for crushing or disintegrating the ore when said sections are moved, to 95 discharge the disintegrated ore through said grate, a combined collecting and air pressure chamber located below said grate, and means for regulably and at will introducing an air blast into said collecting and air pres- 100 sure chamber.

4. In an ore roaster adapted for roasting a columnar charge by internal combustion thereof, a charge-holding roasting chamber, a crushing grate having relatively mov- 105 able crushing sections arranged and adapted for directly supporting the columnar charge in said chamber and for crushing or disintegrating the ore when said sections are moved, to discharge the disintegrated 110 ore through said grate, roller bearings supporting said grate, guards carried by the grate sections adapted for the protection of the roller bearings, and means for introducing a blast of air upwardly through said 115 grate into a charge supported thereon for the purpose of roasting the charge solely by internal combustion thereof.

5. In an ore roaster adapted for roasting a columnar charge by internal combustion 120 thereof, a charge-holding roasting chamber, a crushing grate having relatively movable crushing sections arranged and adapted for directly supporting the columnar charge in said chamber, said sections having grate 125 bars equipped with teeth or projections adapted for crushing or disintegrating the ore when said sections are moved, to dis-

charge the disintegrated ore through said grate, and means for introducing a blast of air upwardly through said grate into a charge supported thereon for the purpose 5 of roasting the charge solely by internal combustion thereof.

6. An ore roaster having a charge-holding roasting chamber, in combination with a grate composed of relatively movable sections whose outer parts are overhung by the 10 lower ends of the walls of said roasting chamber, and a combined air pressure and collecting chamber located below said grate.
